DESIGN FOR A POKER CHIP TRAY

Charles Marcus Dicus, Waynesville, N. C.

Application November 19, 1938, Serial No. 81,231

Term of patent 14 years

To all whom it may concern:

Be it known that I, Charles M. Dicus, a citizen of the United States and a resident of Waynesville, in the county of Haywood and State of North Carolina, have invented the new, original, and ornamental Design for a Poker Chip Tray, of which the following is a specification, reference is had to the accompanying drawing forming part thereof, in which:

Figure 1 is a perspective view of the poker chip tray, showing my new design.

Figure 2 is a plan view of the poker chip tray.

I claim:

The ornamental design for a poker chip tray, as shown.

CHAS. MARCUS DICUS.
